UNITED STATES PATENT OFFICE.

JACQUES NESSEL AND JEAN FRÉDÉRIC GOUIN, OF BREST, FRANCE.

LONG-DISTANCE RELAY MAGNETIC TELEPHONE.

SPECIFICATION forming part of Letters Patent No. 678,509, dated July 16, 1901.

Application filed April 14, 1900. Serial No. 12,789. (No model.)

To all whom it may concern:

Be it known that we, JACQUES NESSEL and JEAN FRÉDÉRIC GOUIN, citizens of the Republic of France, and residents of 17 Rue Arago, Brest, France, have invented certain Improvements in Long-Distance Relay Magnetic Telephones, of which the following is a specification.

Our invention relates to long-distance relay magnetic telephones for ordinary and submarine use.

As is well known, when speaking in front of the disk of a magnetic telephone of any kind an undulatory or induced current is immediately produced, the receiver at the other station reproducing the vibrations of the transmitter under the influence of this current.

In order that our invention may be readily understood, we will describe the same, by way of example, with reference to the accompanying drawings, in which—

Figure 1 is a longitudinal section through our form of relay. Fig. 2 is a cross-section through the same. Fig. 3 shows a modification of Fig. 1, and Fig. 4 is a diagrammatic view of a telephone-line according to our system. Fig. 5 represents a desirable modification of the diaphragm of the relay.

Referring to the accompanying drawings, A is the transmitting-station, B the relay-station, and C the other terminal station. At B instead of applying the receiver to the ear it is placed in front of an exactly similar instrument, the vibrating disk of which has been previously removed. When the magnets have been suitably adjusted, if conversation takes place from A the disk at B will vibrate equally upon one side as upon the other, and these vibrations will give rise in the circuit of the added telephone to a fresh current which in its turn will act upon the disk at C. What has been effected then is to replace the ear receiving the message in ordinary circuits by a second telephone, communication having taken place from A to C through B, where the line-wires are interrupted, each extremity being run to earth, passing through the bobbins and the body of the instrument or relay B.

As shown in Fig. 1, the cable b enters the relay and is connected to the bobbins by

means of the terminals $n n'$. From the bobbins the cable is connected to earth by means of the terminals $o o'$ and the outer casing a of 55 the relay.

This instrument consists of three essential parts—that is to say, the body or casing a , of cast metal, constructed, preferably, of torpedo shape and consisting of four parts united by 60 bolts. The cable b passes in at each extremity of the apparatus through a hermetic joint c . The wires d of the armor of the cable, if this latter is a coast or medium size cable, leave the cable where it enters the relay and are 65 united upon the median circumference of the double-cone body or casing a in such a manner as to be firmly fixed beneath the screws e , which are arranged for this purpose upon the opposite cone. Above these wires and 70 around the circumference of the body of the apparatus a ligature f is formed at intervals in such a manner as to constitute a rigid whole and obviate all likelihood of rupture. In the cast-metal casing two apertures h are 75 formed to admit of the passage of the melted paraffin which is used to fill the spaces between the two casings, and thus insure more perfect insulation.

If the apparatus is to be employed for the 80 purpose of connecting two overhead lines one with the other, a wooden casing of any suitable kind may be employed.

The second essential portion of the apparatus is a brass casing g , which is also hermetically closed and contains the relay.

The third essential feature of the apparatus consists of an assemblage of several magnets x , provided with bobbins i . These magnets are arranged opposite one another 90 and separated by means of one or more vibrating disks k .

A simple or single acting apparatus comprises only one plate k between the magnets, (see Fig. 1,) while the double-acting form of 95 apparatus is provided with two plates $k k'$. (See Fig. 3.) The magnets may be placed opposite one another by poles of like or opposite sign. Each of these methods presents its advantages and disadvantages. In the 100 first case the magnetic field is intense, but confused. In the second case demagnetization is possible. In order to obviate these defects, we adopt a combined form in which

the two magnetic fields are absolutely separated one from the other. With this object we provide an assemblage of two plates or disks k k' , Fig. 3, magnetically insulated one 5 from the other by an interval of one centimeter, which is maintained by means of a collar m , which separates them. A nut l , of non-magnetic material, maintains absolute parallelism.

10 Numerous experiments have led us to triplicate the thickness of the disks or diaphragms by means of annular plates of metal k^2 , Fig. 5, arranged on each side at the center of said diaphragms. This addition does not sensibly 15 detract from the energy of their vibration and conserves the lines of force of the magnet in a greater measure.

In the case of the application of a single 20 plate k , such as that shown in Fig. 1, the collar m is removed.

The apparatus constructed in accordance 25 with our invention presents many advantages over similar appliances as heretofore constructed.

Our form of relay is especially applicable 30 to submarine lines.

Having now particularly described and ascertained the nature of our said invention and in what manner the same is to be performed, 35 we declare that what we claim is—

1. In a long-distance-telephone relay, the combination of a hermetically-closed inner non-magnetic casing, energizing-magnets and diaphragm inclosed thereby, earth-terminals on said casing to which the bobbins of the 35 magnets are connected, a hermetically-closed outer casing inclosing said inner casing, conductors extending from said terminals to said outer casing, and a chamber separating said casings and adapted to receive a filling or 40 packing of insulating material, as paraffin.

2. The combination of the inner hermetically-closed casing, the diaphragm and magnets therein, the outer hermetically-closed 45 double-cone-shaped casing, electrical connections extending from said magnets to the outer casing, and a divided cable the conductors of which enter the opposite ends of the outer casing and are connected to the magnets inclosed in the inner casing, and the armor of 50 which is carried over the outer casing and secured to the cones thereof.

In testimony that we claim the foregoing we have hereunto set our hands this 29th day of March, 1900.

JACQUES NESSEL.
JEAN FRÉDÉRIC GOUIN.
